FEEDING MECHANISM FOR SEWING-MACHINES.

1,252,666.

Specification of Letters Patent.

Patented Jan. 8, 1918.

Application filed October 20, 1914. Serial No. 867,600.

To all whom it may concern:

Be it known that we, HERBERT CORRAL and JAMES MOIR FORBES, subjects of the King of the United Kingdom of Great Britain and Ireland, residing, respectively, at Parkview, Helensburgh, Dumbartonshire, Scotland, and Scotstoun, Glasgow, Scotland, have invented certain new and useful Improvements in Feeding Mechanism for Sewing-Machines, of which the following is a specification, reference being had therein to the accompanying drawings.

This invention relates to improvements in feeding mechanism for sewing machines, and has for its object to provide simple, efficient and convenient means of adjusting the feed from a point above the work-plate of the machine.

The improvements comprise a feed-rocker connected to a feed-bar of the usual construction and provided with a crank-arm which receives motion from the driving shaft of the machine through a sliding connection with a feed-actuating pitman, the latter being provided with a strap to embrace an eccentric on the said driving shaft. The crank-arm of the feed-rocker is in the form of a split tubular post. Slidably fitted upon the said post is a block having a forked lateral lug, and slidably fitted within the cavity in said post is an internally screw-threaded annular member having a lateral projection passing through the split or slotted wall of the post and disposed intermediate the members of said forked lug, the arm being secured to the forked lug by means of a suitable screw or bolt.

The end of the pitman or eccentric rod has a pivotal connection with the slide block, and an adjusting screw is employed to vertically adjust the block relatively to the tubular post. The adjusting screw fits within the cavity of the post and engages the internally threaded member of the block, and its notched end may be manipulated, by means of a key or the like passing through an aperture formed in the bed-plate to raise or lower the block as desired. By the means thus briefly described, the sliding connection between the feed actuating pitman and the feed-rocker may readily be moved toward or from the axis of movement of the latter to vary the length of feed.

In the drawings, Figure 1 is a perspective

view of the improvements as applied to a 55 Singer sewing machine, and Fig. 2 is a detail sectional view of the tubular post, the slide block, the adjusting screw and certain other connected parts.

The improvements are shown applied to a 60 machine comprising the bed-plate A, hollow standard B and work-plate C. The usual driving-wheel 1 is indicated by dotted lines and is carried by the driving-shaft 2, the latter rotating within suitable bearings supported by the standard B and the bearing support D rising from the bed-plate of the machine. The feed-dog 3 is adjustably secured by means of the stud-screw 4 upon the feed-bar 5 which overhangs the feed-lift eccentric 6 on the driving-shaft 2. A short pitman 7 is provided with a strap 8 which embraces the eccentric 6, the pitman being connected to the feed-bar 5 by the pin 9. The enlarged apertured rear end of the feed-bar is fitted between the apertured branches of a yoke y formed at the end of the arm 10^x of the feed-rocker 10, being pivotally connected to the yoke by means of a pin 5^x, the latter being held in position by the clamping screw 11.

Rising from the bed-plate A are two spaced lugs a, each lug being apertured to receive a center-screw 12. The screws 12 engage axial seats formed in the feed-rocker 85 10 and afford pivotal supports therefor. A tubular crank-arm 13, forming part of the feed-rocker, receives motion from the driving shaft 2 through the instrumentality of an eccentric rod 17. The base of the crank-arm is formed as a strap 13^x to embrace the shaft of the feed-rocker, the strap being held in position by means of two clamping screws 14. The connection between crank-arms 13 and eccentric rod 17 comprises a slide block 95 15 loosely fitted upon the crank-arm and formed with an apertured boss 15^x adapted to receive a pin 16 which pivotally connects the boss with the yoked end 18 of the eccentric rod. The opposite end of the eccentric 100 rod is provided with a strap 20 which embraces the eccentric 21 upon driving shaft 2.

It will be seen that adjustment of the slide block 15 toward or from the axis of movement of the feed-rocker 10 will vary the 105 length of movement imparted to the feed-bar 5 and hence will effect a change in the length of stitch. To this end, the tubular

crank-arm 13 is formed with a slot 13^{xx} to receive the lateral projection 22 of an internally screw-threaded annular member 23 slidably fitted within the cavity of the 5 crank-arm. The projection 22 is disposed intermediate the members of a forked lug 24 projecting laterally from the block 15, and is secured to the lug by means of a screw 25. An adjusting screw 26 fits within the cavity 10 of the tubular crank-arm and engages the member 23 of the slide block. The adjusting screw is held against endwise movement, and for this purpose it is provided below its notched head with a flange 26^x held between 15 a lower washer 27 and upper washers 28, 29. The lower washer rests upon a seat ^s formed angularly of the tubular-arm, and the upper washers are held in position by means of an apertured cap 30 which is threaded to engage 20 threads formed in the upper internal wall of the tubular arm. The washer 28 may be made of yielding material to compensate for wear in the lower washer 27—the latter being preferably formed of metal.

25 The upper end of the tubular-arm 13 projects immediately below the work-plate C, and the latter is formed with an aperture 31 to permit manipulation of the adjusting screw from a point above the work-plate by 30 means of a key, screw driver or the like. By turning the screw 26 the slide block 15 will be raised or lowered upon the arm 13, and the connection between the pitman 17 and feed-rocker 13 will be correspondingly 35 changed in position to alter the length of feed.

40 The arrangement above described provides a simple, convenient and effective means for obtaining instantaneous adjustment of the length of feed, while retaining the same rigidity as the slotted quadrant adjusting means of well known construction.

45 It will be understood that the invention is not limited to the precise construction and arrangement of elements herein illustrated. For instance, it is evident that the slide-block 15 may be connected to the element 23 by means other than the forked lug 24; and any suitable means may be employed for holding the adjusting screw 26 against endwise movement.

Having thus set forth the nature of the invention, what we claim herein is:—

1. In feeding mechanism for sewing machines, the combination with a feed-dog, a feed-rocker and an operative connection between the feed-dog and the feed-rocker, of a driving shaft, a tubular crank-arm carried by said rocker, a reciprocating element operatively connected to the driving shaft, a slide-block engaging the exterior surface of the crank-arm and connected with the said reciprocating element, and an adjusting screw held against endwise movement with 60 65 in the said crank-arm and adapted to move

the slide-block toward and from the axis of the feed-rocker.

2. In feeding mechanism for sewing machines, the combination with a feed-dog, of means for imparting operative movements 70 to said feed-dog including a feed-rocker, a tubular slotted crank-arm connected to the rocker, a driving shaft, a slide-block mounted upon the crank-arm, a reciprocating element connecting the driving shaft and slide-block, an internally-threaded block fitted within the cavity of the crank-arm, a member projecting through the slot of the crank-arm and connecting the said blocks, an adjusting screw fitted within the crank-arm 75 and engaging the internally-threaded block, and means for holding the said adjusting screw against endwise movement.

3. In feeding mechanism for sewing machines, the combination with a feed-dog, of 80 means for imparting operative movements to the feed-dog including a feed-rocker, a tubular slotted crank-arm connected to said feed-rocker, a slide-block mounted upon said crank-arm and provided with a lateral lug, 85 an internally-threaded block fitted within the cavity of the crank-arm and formed with a projection passing through the slotted wall of the crank-arm and secured to the lug of the slide-block, an adjusting screw 90 fitted within the cavity of the crank-arm and engaging the internally-threaded block, a driving shaft, and a reciprocating element connecting said driving shaft and the slide block.

4. In feeding mechanism for sewing machines, the combination with a work-support having an aperture therein and a feed-dog, of means for imparting operative movements to the feed-dog including a feed-rocker, a tubular crank-arm connected to 105 said feed-rocker and extending upwardly therefrom toward said aperture, an internally-threaded slide-block fitted within the cavity of the crank-arm, a driving shaft, a reciprocating element operatively connected to said driving shaft, a connection between said reciprocating element and the slide-block, and an adjusting screw fitted within the crank-arm and engaging the slide-block, the said adjusting screw moving with the crank-arm below the work-support and into register with said aperture whereby the length of feed may be readily adjusted without disturbing the machine.

5. In a feed mechanism for a sewing machine having a work-support provided with an aperture therein, in combination, a feed-bar rocker having a substantially vertical arm, means for oscillating said rocker comprising a sleeve adjustable on said arm toward and from the axis of the rocker, and a screw for adjusting said sleeve, the head of said screw lying below and in registry with said opening, whereby the length of 110 115 120 125 130

feed may be readily adjusted without disturbing the machine.

6. In a feed mechanism for sewing machines, in combination, a work-support having an aperture therein, a feed-bar, and means for imparting thereto a longitudinal, fabric-feeding motion, comprising a feed-rocker having a substantially vertical arm, mechanism for oscillating said rocker, and connections between said rocker and said mechanism comprising a member longitudinally adjustable upon said vertical arm, and means for adjusting the same, said last means being located below and in registry 15 with the opening in the work-support.

7. In feeding mechanism for sewing machines, in combination, a work-support having an aperture therein, a feed-dog, and means for imparting to said dog a longitudi-

nal, fabric-feeding motion comprising a 20 feed-rocker, a driving shaft, a connection between said driving shaft and feed-rocker including a block slideable upon the feed-rocker and adjustable toward and from the axis of the latter, and means for so adjusting said block, said means being located below the work-support and in registry with the opening therein, whereby the stitch length adjusting means is at all times readily accessible to the operator. 25

In testimony whereof, we have signed our names to this specification, in the presence of two subscribing witnesses.

HERBERT CORRALL.
